Johnson & Cox Assignees of Samuel Clark, Troy, N.Y.
Letters Patent No. 249. Dated November 13th 1844.

The schedule referred to in these Letters Patent and matter of parts of the same.

Whereas, whom it may concern. Be it known, that Samuel Clark of Troy, in the County of Rensselaer and State of New York, have invented or produced a new design of parlor stone plates, which he calls the Commercial parlor. A. S. and do hereby declare, that the following is a full, clear and exact description of the same, reference being had to the annexed drawings making a part of this application, in which Fig. 1 is a view of the front and Fig. 2. of the end plates of the stove.

In the drawings I have represented only part of the arrangement the remainder being a repetition of and corresponding with that represented on the other parts of the plates as is plainly to be seen by reference to the drawings.

What I claim as new and desire to secure by letter patent is the design and configuration of an ornamental stove plates, as herein described and represented in the annexed drawings.
